UNITED STATES PATENT OFFICE.

JAMES M. MARTIN, OF KNOXVILLE, TENNESSEE, ASSIGNOR OF ONE-HALF
TO EDWARD W. KIRBY, OF SAME PLACE.

DESIGN FOR A PATTERN FOR WIRE FABRIC.

SPECIFICATION forming part of Design No. 26,235, dated November 3, 1896.

Application filed October 3, 1895. Serial No. 564,554. Term of patent 14 years.

To all whom it may concern:

Be it known that I, JAMES M. MARTIN, a citizen of the United States, residing at Knoxville, in the county of Knox and State of Tennessee, have invented a new and original Design for a Pattern for Wire Fabric, of which the following is a specification.

This invention relates to a new and original design for a pattern for wire fabric, and it has for its object to provide a design of this character that shall be both useful and ornamental.

The leading feature of the design resides in a series of longitudinal rows of elliptic lanceolate figures having their pointed ends intersecting, and a series of longitudinal rows of hour-glass-shaped figures alternating with the rows of elliptic lanceolate figures, said elliptic lanceolate and hour-glass-shaped figures alternating with each other transversely of the fabric.

In the drawing the figure is a plan view of a wire-fabric pattern embodying the herein-described design.

Referring to the drawing, the numeral 1 designates serpentine lines arranged in longitudinal pairs and meeting each other at regularly-spaced intervals to form a series of longitudinal rows of elliptic lanceolate figures 2, having their pointed ends intersecting. Parallel transverse wires 3 intersect the points of the figures 2 and with the lines 1 form a series of longitudinal rows of hour-glass-shaped figures 4, alternating with the rows of elliptic lanceolate figures 2. The elliptic lanceolate figures 2 and the hour-glass-shaped figures 4 alternate with each other transversely of the fabric.

What I claim is—

The design for a pattern for wire fabric herein shown and described.

In testimony that I claim the foregoing as my own I have hereto affixed my signature in the presence of two witnesses.

JAMES M. MARTIN.
